[57] CLAIM

The ornamental design for a game ball catcher and holder, as shown and described.

DESCRIPTION

FIG. 1 is a perspective view of a game ball catcher and holder showing our new design;

FIG. 2 is a top plan view thereof with the lanyard shown fragmentarily;

FIG. 3 is a side elevational view thereof;

FIG. 4 is a bottom view thereof; and

FIG. 5 is a rear end elevational view thereof.
